UNITED STATES PATENT OFFICE.

NATHANIEL LOMBARD, OF BOSTON, MASSACHUSETTS.

LASTING-MACHINE.

SPECIFICATION forming part of Letters Patent No. 507,550, dated October 31, 1893.

Application filed November 21, 1892. Serial No. 452,659. (No model.)

To all whom it may concern:

Be it known that I, NATHANIEL LOMBARD, a citizen of the United States, residing at Boston, in the county of Suffolk and State of Massachusetts, have invented certain new and useful Improvements in Lasting-Machines; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to power lasting machines and consists in providing two sets of lasting fingers, an upper one and a lower one, which are adapted to grip the edge of the leather upper or vamp automatically and hold 20 it, while the act of lasting is being performed, these several lasting fingers being operated to act conjointly by means of fluid-impelled pistons or plungers.

25 The important feature to be noticed in my invention is that the act of lasting is performed through the agency of fluid-impelled pistons acting upon the lasting fingers in such manner that no hand-operated jaws are employed.

Briefly described, my invention consists in 30 providing two groups of lasting fingers which co-operate simultaneously in pairs, upper and lower. Further in the arrangement of the said lasting fingers, together with a series of fluid-impelled pistons so disposed that the 35 edge of the leather upper shall be seized at the will of the operator and then pulled or drawn over the last.

A further feature consists in subsequently 40 providing for the release and removal of the top group of lasting fingers, the upper of the above being now held by the lower lasting fingers against the last until the act of tacking is accomplished.

Another and important feature is contained 45 in the mechanism provided by which to control the movements of the several fluid-operated plungers and thereby the lasting fingers; said mechanism consisting in pressure and vacuum chambers together with means, 50 whereby the pistons are advanced or withdrawn as desired.

By the improvements which are embodied

in my present invention I am enabled to equalize the action of the several pairs of lasting fingers, and moreover I provide adjustments 55 for the upper set, whereby I am enabled to last either a right or left boot or shoe with equal facility and without any previous or preliminary adjustments. That is by a slight movement of the hand the upper group of 60 lasting fingers are adapted to suit a boot or shoe for either foot.

The drawings represent in Figure 1 a side view in sectional elevation of a lasting machine embodying my invention. Fig. 2 is a 65 front view in sectional elevation on line 2. 2. in Fig. 1. Fig. 3 is a vertical section of two of the upper groups of lasting fingers and carriage enlarged, and showing a modified construction. Fig. 4 is a transverse section on 70 line 4. 4. of that portion illustrated in Fig. 3.

In the present instance I have shown a casting or frame at 2 adapted to support a last 3 suitably mounted, while a shoe upper is shown at 4 in position for lasting purposes. Upon 75 this standard and located laterally on either side of the last are two groups of vertically disposed lasting fingers 5, 6; these co-operate in pairs, the individual members of each pair being indicated by the numerals 1, 2, 3, 4 as 80 co-efficients while corresponding numerals act conjointly; hence 5' and 6', 5² with 6² and so on.

Since the mechanism which I am about to describe serves to control each pair of lasting 85 fingers in exactly the same manner, and as the method of mounting, adjusting and operating each pair is the same respectively in each group, I shall proceed to describe but one such pair of fingers leaving it to be understood that in the act of lasting the several pairs, which together form the two groups of lasting fingers, then act conjointly along the sides of the boot or shoe in process.

Upon the upper part of the upright post of 95 the standard is positioned a swinging arm 7 terminating in a head 8 furnished with a series of parallel holes or borings 9 which act as cylinders to receive vertical plungers or pistons 10, adapted to be operated by fluid supply 100 under pressure through a pipe 12 connecting with a chamber 13 common to all the cylinders. To the lower end of each plunger is attached a block 14 fitted with opposite end

lugs 15 adapted to receive adjusting screws 16 the functions of which will be hereinafter explained. Mounted in longitudinal guides or upon a rod or pin is a carriage 17, which 5 is adapted to move transversely across the last. Where a pin is used as a guide both lugs are shown as integral with the block, but when guides are formed, as illustrated in Figs. 3 and 4 a removable plate is provided 10 in order to enable the carriage to be slipped into its guides in the block. Furthermore secured to the carriage and pendent therefrom are two oppositely disposed swinging lasting fingers 6', 6'', which terminate at their 15 lower free ends in heads 18, while horizontal arms 19 grooved at 20 on the under side project laterally therefrom and at right angles to the longitudinal axis of the last. A short pin or bolt 21 pivotally attached to one of 20 the fingers and having screw thread engagement with the other as shown in Fig. 2 together with a coiled spring 23 serves to prevent the fingers from diverging too widely when inactively positioned and caused by 25 the tension of the spring, while they are still free to approach each other. Since the shape and position of these upper lasting fingers causes them to hang slightly from the vertical, it will be understood that a downward or 30 advance movement of a plunger 10 serves to press or force said fingers outwardly against any opposing instrumentality.

In connection with the above described lasting fingers is the adjustment for the carriage 17 on which the said fingers are mounted, whereby such fingers can be positioned for either a right or left boot or shoe. For purposes of explanation I will assume in Fig. 2 that the toe of the last is facing the operator; this will bring the outside of a right shoe 40 on the right, conversely the outside of a left shoe on the left. Consequently to effect the necessary adjustment the respective screws 16 are moved to conform to the contour of 45 the last and when a right shoe is to be lasted the operator passes his hand along, thereby wiping the several carriages and slides them over until each one brings up against its adjusting screw, with the result to bring every 50 carriage in readiness to last a right boot or shoe. By converse action an opposite effect is produced, and the fingers are placed suitably to last a left shoe or boot.

To co-operate with the upper lasting fingers 55 6', 6'' I have arranged the lower lasting fingers 5', 5'' respectively. These consist of two vertically positioned bars having curved ends, which bend in transversely over the last and terminate in rounded extremities 24, adapted 60 to co-operate automatically with the heads 18 in order to grip the shoe upper. Upon reference to Fig. 4 it will be seen that the upper portion of the extremities 24 of each lasting finger is wedge shaped, and adapted to engage 65 in the V grooves or guides 20 in the arm 19 on the upper lasting fingers. This positive engagement serves to align vertically the

heads of the respective lasting fingers and compels them to assume their proper positions every time in the act of lasting. To 70 support said fingers and at the same time to equalize their movements, since two, one on each side of the last, are operated by the same plunger, I have attached the lower ends of the fingers to a horizontal fulerum rod 25, 75 the latter being adapted to rock on a fulerum block 26 spring-mounted in a fixed part of the frame 2, which here consists in a lateral web or plate 27. To the under side of said plate is bolted the lower plunger-head 28 of a 80 construction similar to the upper one 8. The plungers in this lower head are shown at 29. To operate the lower group of lasting fingers, a rocking arm 30 is attached to the lower extremity of each plunger, while bands 31 fastened to the free ends of said arm extend upward about anti-friction rollers 32 and connect with the lasting fingers preferably in their upper portion. Thus as the fluid, admitted into the chamber 34, which is common to the cylinders, forces said plungers downwardly the bands draw the lasting fingers both downwardly and inwardly, this downward action being compensated for by the spring-mounted fulerum block 26. To 95 operate and control the said lasting fingers at pleasure and to advance or retract either group simultaneously and automatically I have found the following method inexpensive, practical, and efficient. Two liquid-tight vessels 40, 41, are provided respectively for pressure and vacuum service; each is furnished with gages as indicators of their condition, while a pumping apparatus 42 interconnects the two pipes 43, 45. Oil, preferably employed as a liquid, is first poured into the vacuum reservoir, when reciprocations of the pump force the oil into the tank 40, where it is retained under pressure by aid of the check-valve 46, while the transfer of such 105 liquid causes a vacuum to be formed in the vessel from which the liquid is taken and maintained by a check valve 50. A pipe 48 leading from the pressure reservoir interconnects with each plunger head 8, 28 by 110 means of branch pipes 49, 12, while three-way valves 51, 52 control communication between said pipes and the pressure reservoir, as likewise between said heads and the vacuum vessel by means of the pipe 53. 115 Hence by aid of levers, shown as 56, 57, or other instrumentalities by which said valves may be shifted quickly, the position, pressure and action of the plungers can readily be controlled. That is both groups can be advanced, or one may be withdrawn, while the other group remains active, or both may be withdrawn, so it is evident that each group is independent of the other, or can be caused to act simultaneously therewith, as circumstances require. 125

The mode of operation and the functions of the various elements above described when assembled as a power lasting machine are as 130

follows: Liquid, preferably oil, is poured into the vacuum vessel 41, whence it is transferred by the pump 42 into the tank 40, and by such transfer a vacuum is formed in 41, and pressure created in 40. This liquid now under pressure is in readiness to be employed for actuating the plungers and either series may now be advanced by opening the valves 51, 52 to their respective supply pipes 49, 12; or either series may be retracted, if already advanced, by allowing the chambered heads to communicate with the vacuum vessel. This is effected by turning the proper valve into such a position, as to shut off the supply pipe and interconnect either pipe 49, 12 with the vacuum vessel, when the plungers are retracted an amount equal to the displacement occasioned by the oil permitted to return to the vacuum vessel 41. Assuming that the valves are now positioned to close communication with both vessels 40, 41, the last 3 with its inner sole 54 and leather upper is then put in place. The position of the lasting fingers is as shown in Fig. 3 of the drawings. Liquid under pressure is now admitted through the pipes 49, 12 into the plunger-heads 8, 28 by opening the valves 51, 52, with the result to advance their plungers and actuate the lasting fingers, the lower group advancing inwardly and slightly downwardly until it meets the upper group which now rests upon the in-sole, the individual fingers 6', 6², 6³ acting with an outward thrust to oppose the co-operating lasting fingers 5', 5², 5³, acting with an inward thrust; as a consequence the edge of the leather upper is grasped and held between the heads 18, 24. At this moment the lower fingers 5', 5² are now subjected to the full liquid pressure, the valve 51 being open. In order to advance the lower fingers inwardly, while the act of lasting is being performed, the valve 52 is slightly opened to the vacuum with the result that the upper fingers are allowed to yield as their plungers retract, the pressure between the fingers, upper and lower pairs, remaining constant, since the lower fingers advance inwardly only as fast as the upper ones approach each other. In this way the upper of the shoe is stretched and drawn tightly over the last. At the time this act is completed the lower fingers 5', 5², 5³ bear upon the last and hold the leather firmly against said last. In order to finish the act of lasting and tack the upper in place, the valve 52 is turned to close pipe 48 and open the pipe 12 which now connects with the pipe 53, and is so held until the upper group 6', 6², 6³ is released and withdrawn sufficiently to permit the entire group of fingers, plungers, and plunger-head to be swung to one side. After tacking has taken place, the valve 51 is turned to allow the fluid in part in the plunger head 28 to return to the vessel 41. When such steps are completed the pump 42 may be operated to return the oil now in vessel 41 to the tank 40 and thus restore the vacuum in one and the pressure in the other. However

I have found by experiment that the pump 42 does not require to be operated except at long intervals. Prior to the activity of the lasting fingers the several carriages 17 are pushed over to the right or left according to the boot or shoe to be lasted, while the fingers 5' 6'; 5² 6²; adjust themselves to conform to the top and side contour of the last at their respective points of contact. Any degree of grip between the fingers can be secured, while the pull upon the leather in the process of lasting may likewise be varied at the will of the operator.

This machine is very rapid in its work, since the leather upper is seized simultaneously at all points along its edge by the two groups of lasting fingers, which act automatically. In this way I avoid the use of manually operated jaw-members, as hitherto employed. The toe and heel portions of the upper may be lasted by mechanism of any approved form, but such I have omitted, as having no bearing upon my present improvements.

I am not aware that a lasting machine has ever been constructed in which the edge of the leather upper has been grasped by two groups of lasting fingers, upper and lower, operated automatically by fluid pressure. Hence I do not desire to be limited to the precise construction of the several instrumentalities provided by which such effect is obtained, as the various elements may be modified somewhat in form and still be within my invention.

The dotted arrows in Fig. 2 indicate the direction in the flow of the liquid whenever either valve 51, 52, is so turned as to unite the pipes 12, 49 with the pipe 53 to the vacuum vessel 41.

What I claim is—

1. A power lasting machine having a stationary last, and composed of two groups of lasting fingers, adapted to act automatically in pairs, an upper finger with a lower finger, and conjointly grip the edge of the leather upper, together with fluid-impelled plungers for actuating said fingers, substantially as and for the purposes herein described.

2. A power lasting machine having a fixed last, and composed of two series of fluid-impelled plungers, two groups of lasting fingers, interconnecting mechanism between said plungers and their fingers, together with means whereby said plungers are reciprocated to cause the groups of lasting fingers to act conjointly in pairs, one upper finger and one lower finger, and thereby grasp the edge of the leather upper, substantially as specified.

3. In a power lasting machine, two chambered heads, a series of reciprocating plungers therein, and mechanism by which fluid pressure controls said plungers, combined with two groups of lasting fingers, said groups being composed of similarly operated lower fingers arranged on each side of the last, together with like operated upper fingers, and mechanism which unites said fingers and

plungers whereby the several members composing the upper and lower groups shall set conjointly in pairs to automatically grasp the leather, substantially as set forth and stated.

5. 4. In a lasting machine, the combination with a chambered head, a series of fluid-impelled plungers, and an adjustable carriage attached to each plunger, of a pair of lasting fingers composing a group and pivoted upon 10 said carriage, said lasting fingers adapted to cooperate with a pair of lasting fingers composing a second group, all operating, substantially as and for purposes specified.

5. In a lasting machine, a pair of lasting 15 fingers composing a group, a spring-mounted fulcrum bar, and a fluid-impelled plunger, with connections from said plunger to actuate the lasting fingers, combined with a pair of lasting fingers constituting a second group, a 20 carriage adjustable transversely of the last and adapted to support said fingers, and a fluid-impelled plunger, the two plungers serving to automatically control the two groups of lasting fingers which act conjointly, substantially as explained.

6. In a lasting machine, the combination with two chambered heads, a series of reciprocating plungers therein, and two groups of lasting fingers operating conjointly in pairs, 30 to grip the upper automatically of the closed vessels respectively for pressure and vacuum service mechanism for uniting the plungers with the lasting fingers, connections from said vessels to each chambered head, and means 35 by which said chambered heads are subjected to pressure or vacuum influence of said vessels, substantially as herein stated and described.

7. In combination with the frame of a last-

ing machine, a spring fulcrum block, an oscillating fulcrum bar thereupon, lasting fingers pivotally secured at each end of said bar, and a chambered head, a series of fluid-impelled plungers therein, flexible connections, which unite each plunger with a pair of lasting fingers, which latter are adapted to press the upper of the shoe against the last during the act of tacking, substantially as set forth.

8. In a lasting machine, the combination with a stationary last; two series of reciprocating plungers two groups of lasting fingers, each operated by a plunger interconnecting mechanism, between said plungers and their fingers, together with means whereby the top group of lasting fingers is adapted to swing 55 bodily from over the last at stated times, substantially as and for purposes stated.

9. In a lasting machine the combination with a fluid-impelled plunger suitably mounted, and a carriage affixed thereto, of a pair of 60 lasting fingers supported by said carriage, a grooved arm laterally of each finger, and an adjusting screw, which connects the two fingers, substantially as explained.

10. The combination with two series of fluid 65 impelled plungers, and two groups of lasting fingers connected with and operated thereby, of a series of arms, one laterally from each member of one group of fingers and adapted to engage with and guide the extremities of 70 the other and cooperating group of lasting fingers, substantially as set forth.

In testimony whereof I affix my signature in presence of two witnesses.

NATHANIEL LOMBARD.
